UNITED STATES PATENT OFFICE.

WILLIAM LANE HUTSON, OF ST. LAWRENCE, NORTH CAROLINA, ASSIGNOR
OF ONE-HALF TO THOMAS A. BROOKS AND NOAH R. HARRIS, BOTH OF
SAME PLACE.

SEED-PLANTER.

SPECIFICATION forming part of Letters Patent No. 295,765, dated March 25, 1884.

Application filed August 27, 1883. (No model.)

To all whom it may concern:

Be it known that I, WM. LANE HUTSON, of St. Lawrence, in the county of Chatham and State of North Carolina, have invented a new and useful Improvement in Seed-Planters, of which the following is a full, clear, and exact description, reference being had to the annexed drawings, forming part of this specification.

10 This invention relates to the class of planters in which a plow is provided with a removable hopper and means for dropping and covering the seeds; and the invention consists of the construction hereinafter described and claimed.

15 In the drawings, Figure 1 is a side elevation, partly in section, showing my improved planter. Figs. 2 and 2½ are detail views of the dropping-slide, and Fig. 3 is a detail of the coverer.

A indicates a plow, having beam B, handles C, and stock D.

20 To the stock and the round E of the handles is attached an open frame, F, carrying a wheel, G.

25 To the frame F is pivoted a bent lever, H, having a bifurcated end, I, arranged in engagement with two pins, J, secured to one side of the wheel, and adapted to oscillate the lever

30 in turn. The bifurcations of the end I of the lever are bent outwardly from each other, and the pins J are arranged on opposite sides of the axle of the wheel G, so that each pin in turn is moved between the bifurcations, to lift

35 and then depress the end I. The other end of the lever is pivoted to the dropping-slide K, which is adapted to move in a plane parallel with the front side of the hopper L. The slide K is formed with two tongues, L' M, the

40 former of which is adapted to move against the inner surface of the front side, N, of the hopper, and is provided with a curved bevel surface at O, adapted to push the seeds into the slot P in said side, while the latter tongue, M, is fitted to move on the outer surface of the said side N in a suitable case, Q, and is provided with an opening, R, through which the seeds pass. A spring, S, secured in the slot P serves to push the seeds into the open-

ing R, and through the same when it registers with the opening T in the case Q, from which they drop through the chutes U to the furrow.

V is a thin plate for closing the opening T or regulating its size, and W is a spring 55 adapted to engage with a notched edge of said plate to hold it in any desired position.

The seed-coverer consists of a board, A', having a recess, B', in its lower edge, and provided with a pin, C', on each side of said recess, the pins being set in vertical position and adapted to penetrate the soil on each side of the planted row. The board is connected to two arms, D', which are secured to the rear part of the beam B by a bolt, E', the arms being arranged on opposite sides of the wheel G and its supporting-frame F.

It is designed that a number of removable hoppers shall be provided having suitable dropping devices for different kinds of seed and fertilizers, each being provided with a cross-bar, F', adapted to be bolted to the handles C. It may also be additionally supported by connection with the round E.

The wheel G may be provided with a pulley 75 (not shown) for operating certain of the dropping devices when the bent lever H is not adapted to be used.

The space between the hills of seed is to be regulated by driving-wheels of different sizes 80 and by the number of pins J in the wheel. The height of the plow-beam at front end is to be regulated by the adjustable bolt Z at the rear end.

85 What I claim is—
The combination, with the plow, of the wheel having pins J, the bent lever H, having bifurcations bent outward from each other and arranged in engagement with said pins, the hopper L, the dropping-slide K, having tongues 90 L' and M, formed as described, and the case Q and plate V, substantially as shown and described.

WM. LANE HUTSON.
